CENTRIFUGAL MACHINE

Henry E. Elrod, Houston, Tex.

Application May 4, 1931, Serial No. 534,956

12 Claims. (Cl. 210—69)

This invention relates to centrifugal machines, and more particularly to the type embodying a continuous feed and discharge.

It is an object of my invention to provide a rugged machine adapted to separate liquid and solid matter from a mixture of the two.

It is a further object of my invention to provide a machine which is capable of operating at high centrifugal pressures without rapid deterioration of the parts.

More specifically it is an object of my invention to provide a machine peculiarly adapted for the dewatering of sewage sludge, with a convenient mode of disposition of its constituents.

In the treatment of sewage for municipalities, the drying of the sewage sludge, both from raw and activated sewages, and from the two combined, presents a most difficult and expensive problem. Many methods of drying sludges have been devised, but to date none is quite satisfactory, or economical. Centrifuges have come nearer solving the problem, as to expense, but none has proved satisfactory in practice, particularly on account of the fact that the centrifuges do not strain out sufficient of the solids in the wet sludge to obviate the necessity for further treatment of the expressed liquor, and that the operation of the centrifuges is not continuous, it being necessary to stop operations to "unload" the centrifuge of its dewatered sludge. The centrifuges of the prior art have been very expensive machines, also.

The machine also possesses a distinct utility for the function of removing sand and other extraneous matter from liquid "mud" as used in the oil fields for drilling operations. This adaptation has a great field, as the "mud" is a very expensive commodity. When the "mud" is used, it accumulates sand and chippings of rock, which destroy the pistons of the pumps which are used to force down the "mud" into the deep drilling holes.

It is a further object of my invention to provide camel's hair cloth as a straining medium, which although expensive initially, proves economical because of its durability under high pressure operations.

With the foregoing and other objects in view, the invention will be more fully described hereinafter and will be more particularly pointed out in the claims appended hereto.

In the drawings,

Fig. 1 represents a sectional view of my improved centrifugal machine in connection with the associated system in elevation;

Fig. 2 is an end view of the centrifugal machine;

Fig. 3 represents a sectional view of a modification of the machine illustrated in Fig. 1;

Fig. 4 is an elevation, partly in section of a modified embodiment of my machine;

Fig. 5 is an end view thereof.

In Fig. 1, element 1 represents a tank or any other conventional container adapted to hold liquor such as wet sludge from sewage. A stuffing box 2 is attached to tank 1, to accommodate the hollow rotating shaft 3. Tank 1 and its stuffing box 2 may be replaced by the discharge from any conventional pump, a pipe line, reservoir, or other source of wet sludge, or the like, from which the wet sludge or equivalent material may be transferred to hollow shaft 3. Hollow shaft 3 is supported on conventional journal bearings 4 disposed on suitable stands or pillows 5. Fixedly disposed on shaft 3 is a pulley or gear element 6, through which rotary motion is imparted to shaft 3 from some conventional prime mover.

Centrifuge 7 is fixedly attached to one end of shaft 3 substantially as shown so that it will rotate therewith. This centrifugal machine consists of an end wall 8 which is attached to the shaft 3. Oppositely disposed to this end wall is another one 9 which may have cast therewith or otherwise attached to it radial septa or partitions 10, shown in Fig. 2, of any desired number. These septa 10 are closely fitted to wall 8 by suitable fastening members such as bolts 11, as illustrated. The materials used for these walls and septa may be of any type common to such machines. In the modification shown in Fig. 1 the external peripheral ring or wall 12 has a curved portion which is perforated to allow the expressed liquors to pass through. Another perforated peripheral ring 14, made up of smooth material conforming in shape to ring 12, constitutes the inner surface of said peripheral wall.

These two perforated walls are rigidly connected to the wall 8 and are furthermore braced upon the opposite side by an annular ring 13. Between the peripheral walls 12 and 14, is disposed a filtering medium such as wire mesh or preferably camel's hair cloth. It has been found that the latter resists the high pressures characteristic of this type of machine better than does any other filtering medium. The cross sectional diameter of end wall 9 is less than that of the peripheral wall in order to provide a relief passage 25 for the extrusion of the solid matter which is forced out. The modification in Fig.

3 illustrates a straight type of a peripheral wheel. In this case the end wheel 9 is formed with a lip 16 to provide the proper extrusion channel for the solid material. Otherwise, the elements 5 of this modification correspond to those illustrated in Fig. 1.

10 Centrifuge 7 is entirely enclosed, except as shown, by a suitable hood or cover 17, the object of which is to catch and drain to the outlet 18, the liquor passing into said cover from the interior of the centrifuge 7. Hood 17 is cut away in the circular form at the right of Fig. 1, and a lip 19 is turned inwardly around the complete circumference, to insure complete entrapment 15 of the liquid material. The bottom of hood 17 forms a pan 20 adapted to hold the liquor, which may be drained off through outlet 18.

15 Adjacent the mouth of the centrifuge, formed by ring 13, is disposed a scoop 21 to guide the material that is extruded therefrom upon a conveyor frame 22. This scoop may be fixedly or adjustably mounted upon a bracket member fixed to the conveyor frame as shown.

20 The machine operates in the following manner. With the tank 1 full of wet sludge, or the like, and centrifuge 7 rotating at a sufficient speed to create a proper centrifugal pressure at the periphery of ring 12, wet sludge is admitted to the centrifuge, and the centrifugal force operates to express the liquor from the solids of the sludge through perforations in plate 14 and through filter medium 15 and ring 12, out into cover 17, where it will fall into pan 20, thence 25 through outlet 18 to suitable storage or to waste. The lip 19 of cover 17 will trap all splashing, or trickling liquor and prevent its escape through the side opening in cover 17. As liquor is expressed from the sludge in centrifuge 7 the volume of such sludge will be reduced and additional wet sludge will flow into centrifuge 7 from tank 1, or other source, through hollow shaft 3, to keep centrifuge 8 filled.

30 By virtue of the force of the centrifugal pressure exerted on the mass of sludge in centrifuge 7 between walls 8 and 9, the dewatered sludge near the inner periphery of wall 12 will push out through the annular opening at 25 and be forced centerward until it reaches the inner edge of ring 13, when plough 21 will catch it and throw it upon conveyor 22, or upon the floor to be removed manually. The above operation refers to 35 Fig. 1, but is applicable to Fig. 3 also.

35 The embodiment illustrated in Figs. 4 and 5 provides a feature for continually clearing the interior surface of the peripheral ring or wall of the accumulated material. The structure illustrated in Fig. 4 embodies similar elements to those correspondingly shown in Figs. 1 and 3. 40 However the chamber for the rotating material is of different design. As in Fig. 1, end wall 8 is fixed to hollow shaft 3. The peripheral wall comprising a filtering medium is fixed to wall 8 and reinforced by ring 13. The cooperating wall 45 30 opposite to wall 8 is independently mounted upon a shaft 31, which is co-axial with shaft 3. This wall is illustrated as circular, and may be of plane or concave form. Curved blades 35 are fixed to wall 30, the shapes of which conform to 50 the shape of the inner walls of the rotating chamber, and which upon the relative rotation of the centrifuge and the blades, just clear the centrifuge walls.

55 Rotary motion is imparted to shaft 31 and consequently to elements 30 and 35 by means of a

countershaft 34 displaced from the main shaft 3 and driven therefrom by means of a gear or pulley 36 upon the latter, through a suitable belt or equivalent transmission. Another pulley 37 upon shaft 34 imparts the rotary motion of the latter to shaft 31 by means of a pulley 38 thereupon. The transmission system is so designed that shaft 31 rotates in the same direction as shaft 3 but at a lesser speed.

60 The machine operates in the manner explained in regard to Figs. 1 and 3, with the additional function that the blades 35, rotating at a lesser speed than the centrifuge casing, act as plows, and loosen the mass of solid material for extrusion thereof through annular channel 40. The inclination of the plows may be designed to aid in this effect. The blades 35 will keep the filter cloth 15', or if desired the protective ring 14, as shown in Fig. 1, scraped clean of the de-watered sludge, to render more positive the continuous operation of the machine.

65 It is presumed that the centrifuge may be rotated as a speed sufficient to produce a centrifugal pressure, at the periphery, of several hundred pounds per square inch, which may be 400, which corresponds with the pressures obtained in practice by mechanical presses, such as are used to express oil from cotton seed, etc. However, if such pressure is not readily obtainable, economically, in the given centrifuge, the economical 70 pressure may be augmented, at will, by creating an initial pressure through hollow shaft 3 by means of a pressure pump instead of the gravity flow provided by the tank 1. Given an initial pressure, as described, of 100 pounds per square 75 inch, and a centrifugal pressure of 300 pounds per square inch, an ultimate pressure, at the periphery in the centrifuge, of 400 pounds per square inch will be had.

80 In conjunction with such high pressures, it is necessary to use an improved filtering medium, which is able to satisfy the rigid requirements demanded of it. Camel's hair cloth is peculiarly adapted for this purpose, especially when it is protected on both its sides by the protective plates 85 12 and 14.

85 It is obvious that various changes may be made in the details of construction and design of the above specific description of this invention without departing from the spirit thereof, such 90 changes and modifications being restricted only by the scope of the following claims.

95 Having thus described my invention what I claim is:

1. In a centrifugal machine, a rotatable member comprising an end wall, a peripheral wall fixed to said end wall, a second end wall oppositely disposed and rigidly connected to said first wall, the edge of said second wall being displaced from said peripheral wall, said peripheral 100 wall having perforations therein extending from said first end wall to at least the plane of said second end wall.

105 2. In a centrifugal machine, a rotatable member comprising an end wall, a second end wall oppositely disposed and rigidly connected to said first wall, an outwardly curved peripheral wall fixed to said first end wall and extending on both sides of and displaced from said second wall, said peripheral wall having perforations therein 110 extending from said first end wall to at least the portion thereof opposite the peripheral edge of said second wall.

115 3. In a centrifugal machine, a rotatable member comprising an end wall, a second end wall 120

- oppositely disposed and rigidly connected to said first wall, a peripheral wall fixed to said first end wall and extending on both sides of and displaced from said second wall, said peripheral wall having perforations therein extending from said first end wall to at least the plane of said second wall and a plow cooperating with said rotatable member. 5
4. In a centrifugal machine, a rotating series of chambers formed of one end wall mounted upon a hollow rotatable shaft, a second end wall complementarily disposed and connected to said first wall, radial septa disposed between the said end walls, a peripheral wall contacting with said first 10 end wall and concentrically displaced from the second said peripheral wall having a reticulated portion extending from said first end wall to at least beyond the edge of said second wall and means for introducing a mixture of liquid and solid matter into said chambers to separate the same. 15
5. In a centrifugal machine, a hollow horizontally rotatable shaft, a rotatable member comprising an end wall disposed at the end of said shaft, a series of radially disposed chambers 20 communicating with said shaft at said end adapted to receive a mixture of solid and liquid matter from said shaft, reticulated means rigidly connected to said end wall disposed at the radial extremities of said chambers for straining out the 25 liquid matter, said end wall and reticulated means being so disposed as to provide a relief passage at said extremities for allowing the extrusion of solid matter from said chambers. 30
6. In a centrifugal machine, a hollow horizontally rotatable shaft, a rotatable chamber comprising an end wall disposed beyond said shaft adapted to receive a mixture of solid and liquid matter from said shaft, a reticulated means disposed at the radial extremity of said chamber for straining out the 35 liquid matter, said end wall and reticulated means being so disposed as to provide a relief passage at said extremity for allowing the extrusion of solid matter from said chamber. 40
7. The combination as claimed in claim 6 45 wherein is provided a shield surrounding said rotatable chamber adapted to confine the liquid matter for disposition.
8. In a centrifugal machine, a rotatable chamber comprising an end wall and a reticulated peripheral wall, means for rotating said chamber, a second wall, independently mounted, and disposed within said chamber opposite said end wall with the edge thereof displaced from said peripheral wall, a blade fixed to said second wall 50 transversely thereof and adjacent said peripheral wall adapted to clear said peripheral wall of the material accumulated against it, and means for effecting relative rotary movement between said rotatable chamber and said blade. 55
9. In a centrifugal machine, a rotatable mem- 60 ber comprising an end wall, a second end wall oppositely disposed and rigidly connected to said first wall, an outwardly curved peripheral wall fixed to said first end wall and extending on both sides of and displaced from said second wall, the lateral extremities of said peripheral wall overlying the peripheral edge of said second wall upon opposite sides thereof, said peripheral wall furthermore having perforations therein extending from said first end wall to the opposite extremity thereof laterally beyond and radially within the peripheral edge of said second wall. 65
10. In a centrifugal machine, a hollow rotatable shaft, a rotatable member comprising an end wall disposed at the end of said shaft, a reticulated peripheral wall fixed to said end wall defining a chamber for receiving a mixture of solid and liquid matter from said shaft, a second wall disposed within said chamber opposite said first-mentioned end wall with the edge thereof displaced from said peripheral wall, at least one cleaning member extending transversely of said second wall and peripheral wall mounted on said second wall in proximity to said peripheral wall, means for rotating said shaft and chamber, and 100 means for rotating said second wall at a speed differing from that of said peripheral wall of the chamber, whereby said peripheral wall is cleaned by the movement of said cleaning member. 105
11. In a centrifugal machine, a rotatable chamber comprising an end wall and a reticulated peripheral wall, a second wall, independently mounted, and disposed within said chamber opposite said end wall with the edge thereof displaced from said peripheral wall, means for rotating said chamber comprising a hollow shaft for introducing the material into said chamber at said end wall and directing it towards said second wall, and at least one blade fixed to said second wall transversely thereof and adjacent 115 said peripheral wall adapted to clear said peripheral wall of the material accumulated against it by means of the relative movement between said chamber and said blade. 110
12. In a centrifugal machine, a rotatable chamber comprising an end wall and a reticulated peripheral wall, a second wall, independently mounted, and disposed within said chamber opposite said end wall with the edge thereof displaced from said peripheral wall, means for rotating said chamber comprising a hollow shaft for introducing the material into said chamber at said end wall and directing it towards said second wall, and a plurality of cleaning members 120 extending transversely of said second wall and peripheral wall and mounted on said second wall in proximity to said peripheral wall adapted to clear the latter of the material accumulated against it. 125
13. In a centrifugal machine, a rotatable chamber comprising an end wall and a reticulated peripheral wall, a second wall, independently mounted, and disposed within said chamber opposite said end wall with the edge thereof displaced from said peripheral wall, means for rotating said chamber comprising a hollow shaft for introducing the material into said chamber at said end wall and directing it towards said second wall, and a plurality of cleaning members 130 extending transversely of said second wall and peripheral wall and mounted on said second wall in proximity to said peripheral wall adapted to clear the latter of the material accumulated against it. 135

HENRY E. ELROD. 135
